(57) **CLAIM**

The ornamental design for an electric vehicle charging stand, as shown and described.

DESCRIPTION

FIG. 1 is a top front right perspective of an electric vehicle charging stand showing my new design;

FIG. 2 is a top front right perspective view thereof, shown in an environmental of use;

FIG. 3 is a front view thereof, the back view being a mirror image thereof;

FIG. 4 is a first side view thereof, the second side view being a mirror images thereof;

FIG. 5 is a top view thereof; and;

FIG. 6 is a bottom view thereof.

The broken lines present in the figures are included for the purpose of illustrating portions of the article or environmental subject matter and form no part of the claimed design. The electric vehicle charging stand is shown with a symbolic break in its length. The appearance of any portion of the article between the break lines forms no part of the claimed design.

1 Claim, 4 Drawing Sheets
